United States Patent Office

Des. 215,410
Patented Sept. 30, 1969

215,410

JUG

David G. Hills, Collinsville, Conn., assignor to Monsanto Company, St. Louis, Mo., a corporation of Delaware

Continuation of design applications Ser. No. 8,896 and Ser. No. 8,902, both Oct. 6, 1967. This application May 6, 1968, Ser. No. 12,192

Term of patent 14 years

Int. Cl. D9—01

U.S. Cl. D9—39

FIG. I

FIG. II

FIG. III

FIG. IV

FIG. V

FIG. VI

FIG. VII

FIG. VIII

FIG. I is a perspective view of a jug showing my new design;

FIG. II is a side elevational view thereof;

FIG. III is a top plan view thereof;

FIG. IV is a sectional view taken along the line IV—IV of FIG. II;

FIG. V is a perspective view of a jug showing another embodiment of my new design;

FIG. VI is a side elevational view of the jug of FIG. V;

FIG. VII is a top plan view of the jug of FIG. V; and

FIG. VIII is a sectional view taken along the line VIII—VIII of FIG. VI.

This is a continuation of U.S. applications Serial Nos. D. 8,986 and D. 8,902, each filed on Oct. 6, 1967 and now abandoned.

I claim:

The ornamental design for a jug, substantially as shown and described.
